SEWER FLOODING CONTROL APPARATUS

Edward C. Hanson, Minneapolis, Minn., assignor
to Protection Equipment Co., Inc., Minneapolis,
Minn., a corporation of Minnesota

Application November 12, 1947, Serial No. 785,213

5 Claims. (Cl. 182—1)

1

This invention has relation to a sewer flooding control apparatus adapted to preclude back-up flooding from sewer drain pipes.

An object of the invention is to provide a sewer flooding control apparatus which will be of novel and improved construction.

A further object is to provide a sewer flooding control apparatus wherein will be incorporated desirable and improved features and characteristics of construction novel both as individual entities of the apparatus and in combination with each other.

A further object is to provide in the apparatus, novel and improved mechanism devised to be actuated by sewage to regulate a water flow control valve employed in the manipulation of a sewer drain pipe control valve.

And a further object is to provide a sewer flooding control apparatus of structure as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is a plan view of a sewer flooding control apparatus made according to the invention;

Fig. 2 is a vertical sectional view, partially in elevation and on a reduced scale, taken at the position indicated, generally, by line 2—2 in Fig. 1;

Fig. 3 is a detail sectional view, taken on line 3—3 in Fig. 2;

Fig. 4 is a detail sectional view, taken on line 4—4 in Fig. 1;

Fig. 5 is a detail sectional view, taken on line 5—5 in Fig. 4;

Fig. 6 is a detail sectional view, taken on line 6—6 in Fig. 1;

Fig. 7 is a detail view disclosing parts in elevation as they would appear from the position of line 7—7 in Fig. 1;

Fig. 8 is an enlarged central sectional view detailing a water flow control valve of the apparatus; and

Figs. 9 and 10 are diagrammatic views illustrative of the mode of operation of the water flow control valve disclosed in Fig. 8.

With respect to the drawings and the numerals of reference thereon, a sewer drain pipe 15, adapted to be connected to an ordinary sewer, is contiguous with a casing 16 of a gate valve 17 for

2

controlling a drain pipe (not shown) of a house sewerage or drainage system adapted to lead from a basement, or the like, to the side of the casing 16 opposite the sewer drain pipe 15. The construction and arrangement will be such that said sewer drain pipe 15, the casing 16 and the house system drain pipe will be in longitudinal alignment, with the drain pipes at opposite sides of and securely fastened to said casing in liquid-tight manner.

A stem 18 for the gate valve 17 passes upwardly through a stuffing box 19 which the casing 16 supports.

A pair of upper and lower castings, denoted 20 and 21, respectively, serve as cylinder heads for a cylinder which additionally includes a tubular member 22. The cylinder composed of the heads 20, 21 and the tubular member 22 is supported by the casing 16 and is situated above said casing in spaced relation thereto. As disclosed, tie rods 23 extend through marginal portions of the castings 20 and 21, and nuts 24 on said rods are turned down against the upper surface of the casting 20 and the lower surface of the casting 21 to clamp the tubular member 22 between said castings 20 and 21. Downward extensions on the lower casting 21 integrally or rigidly support spaced apart flange elements 25, 25, and tie rods 26 extend through said flange elements and also through an annular flange 27 on the casing 16. Spacing sleeves 28 on the tie rods 26 and between the flange elements 25 and the annular flange 27 fix the relationship of the casting 21 to the casing 16, and nuts 29 on said tie rods 26 are turned down against upper surfaces of said flange elements 25 and the lower surface of said annular flange 27 to clamp said spacing sleeves 28 between the flange elements and the annular flange. When the nuts 24 are turned down, the opposite ends of the tubular member 22 are firmly and closely seated in annular grooves (not shown) in the castings or cylinder heads 20 and 21 in such manner as to render water-tight the cylinder constituted by said castings or heads and tubular member.

A piston 30, adapted to be reciprocated in the tubular member 22, may be attached to the stem 18 of the gate valve 17 in any convenient and preferred manner. Said stem 18 is slidably guided in the castings or cylinder heads 20 and 21, and stuffing boxes 31 are disposed about the stem and carried by said castings or heads.

The piston 30 is actuated by water under influence of head pressure of a source (not shown) of water supply, as, for example, under head pressure of water employed in an ordinary house supply water system. When said piston 30 is elevated, the stem 18 and the gate valve 17 are raised to open the sewer drain pipe 15 and the house drain pipe to each other, and when the

piston is depressed, the stem and gate valve are lowered to shut off communication between said sewer drain pipe and house drain pipe. Obviously, movement of the gate valve to closed position in the casing 16 will preclude travel of sewage from the sewer drain pipe 15 to the house drain pipe and preclude the passage of sewage into a basement, or the like, when there is back-up of sewage in a sewer to which said casing 16 is connected.

A housing 32, situated at a level below the inner or house end of the sewerage or drainage system from which the house drain pipe leads, provides a float chamber 33 in which a float 34 is mounted to be capable of having up and down movement in a vertical plane. A lower wall 35 of the housing 32 is rigidly supported, as at 36, upon the sewer drain pipe 15, and a centrally disposed opening 37 in said lower wall 35 is contiguous with an opening 38 in an upper portion of said sewer drain pipe 15. The interior surface of the lower wall 35 is of conical configuration and slants downwardly and inwardly from the cylindrical side wall of said housing 32 to the opening 37. The float 34 is adapted to be elevated in response to back-up in the sewer to cause the piston 30 to be depressed, through the instrumentality of water pressure under the influence of head pressure, and the gate valve 17 thus to be moved to closed position, and said float is adapted to be depressed by gravity upon the cessation of sewer back-up to cause the piston 30 to be elevated, also through the instrumentality of water under the influence of said head pressure, and the gate valve thus to be moved to open position.

A water flow control valve 39 consists of a hollowed out body member 40 and a flat base member 41 secured to and against each other, as by headed and nutted bolts 42. A cylindrical valve member 43 is rotatably situated in a chamber 44 of the body member 40 with its peripheral portion 45 snugly engaged against an internal cylindrical surface of said body member, one of its end surfaces 46 engaged against and rotatably slidably over an internal flat surface of the base member 41, and its other end surface 47 contiguous with a part of said chamber 44 at the side of the cylindrical valve member 43 opposite said base member 41. A stem for said valve member 43, fixed against longitudinal movement but freely rotatable in the body member 40, is denoted 48, and a compression coil spring situated between and within reduced portions of the valve stem 48 and the valve member 43, for urging said valve member into pressing engagement with the base member 41, is indicated 49. Said valve member and valve stem are assembled together in such manner that the valve member will be rotatable with the valve stem when this is rotated but will be capable of being resiliently urged by the compression coil spring 49 in direction away from said valve stem and toward the base member 41. A stuffing box 50, disposed about the valve stem 48, is carried by the body member 40. An inlet passageway 51 of the body member 40 is contiguous with the part of the chamber 44 with which the end surface 47 of the valve member 43 is contiguous, and an inlet pipe 52 from a source (not shown) of water supply under head pressure is connected to said inlet passageway 51. An outlet port 53, contiguous at its interior end with the end surface 46 of said valve member 43, extends through the base member 41, and an outlet pipe 54 is connected to said outlet port 53.

A port 55 through the base member 41 is connected to the casting or cylinder head 20 by a

pipe 56, and a port 57 through said base member 41 is connected to the casting or cylinder head 21 by a pipe 58. The ports 55 and 57 are contiguous at their interior ends with said end surface 46 of the valve member 43, and the castings or cylinder heads 20 and 21 include ports contiguous with the interior of the tubular member 22 and to which the pipes 56 and 58, respectively, lead.

10 The valve member 43 includes a relatively short, circumferentially extending passageway 59 for water contiguous at its opposite ends with the end surfaces 46 and 47 and adapted selectively to be aligned with the ports 55 and 57, and 15 also includes a comparatively long, circumferentially extending concavity 60 for water contiguous with said end portion 46, constantly aligned with the outlet port 53 and adapted selectively to be aligned with said ports 55 and 57. The construction and arrangement will be such that when the circumferentially extending passageway 59 is aligned with the port 55 it will be out of alignment with the port 57 and the circumferentially extending concavity 60 will be aligned with said port 57 and out of alignment with said port 55, and when said passageway 59 is aligned with the port 57 it will be out of alignment with the port 55 and said concavity 60 will be aligned with said port 55 and out of alignment with said port 57.

20 In Fig. 9 of the drawings, the valve member 43 is disclosed, in dotted lines, with its circumferentially extending passageway 59 aligned with the port 55 and its circumferentially extending concavity 60 aligned with the port 57, as well as aligned 25 with the outlet port 53. In said Fig. 9, said valve member 43 obviously is situated to permit flow of water under head pressure from the inlet pipe 52 by way of the inlet passageway 51 to the chamber 44 and thence by way of the passageway 59, said port 55 and the pipe 56 into the end portion of the tubular member 22 adjacent the casting or cylinder head 20, and also to permit flow of water from the end portion of said tubular member 22 adjacent the casting or cylinder head 21 by way 40 of the pipe 58, the port 57, the circumferentially extending concavity 60 and the outlet port 53 to the outlet pipe 54.

25 In Fig. 10 of the drawings, said valve member 43 is disclosed, in dotted lines, with its circumferentially extending passageway 59 aligned with the port 57 and its circumferentially extending concavity 60 aligned with the port 55, as well as with said outlet port 53. In said Fig. 10, the valve member 43 obviously is situated to permit flow of water under head pressure from the inlet pipe 52 by way of the inlet passageway 51 to the chamber 44 and thence by way of the passageway 59, said port 57 and the pipe 58 into the end portion 45 of the tubular member 22 adjacent the casting or cylinder head 21, and also to permit flow of water from the end portion of said tubular member 22 adjacent the casting or cylinder head 20 by way of the pipe 56, the port 55, the circumferentially extending concavity 60 and the outlet port 53 to the outlet pipe 54.

30 The float 34 constitutes means for rotatably manipulating the valve stem 48 in such manner that the cylindrical valve member 43 will be situated as in Fig. 9 when said float is in an elevated position and will be situated as in Fig. 10 when the float is in a depressed position.

35 The float chamber 33 is closed, save for the opening 37 and a vertical vent pipe 61 in the upper wall of the housing 32 adapted to lead to

outside atmosphere, and the float 34 is freely movable in said float chamber.

An upstanding vessel 62 for water includes an open, lower portion rigidly supported, as at 63, upon a central portion of an upper wall of the housing 32, and a closure wall, represented 64, on the upper end of said upstanding vessel 62 rigidly supports, as at 65, an inverted, generally U-shape bracket comprising spaced apart legs 66, 66 which are vertically disposed and a base 67 which is horizontally disposed and situated in vertical alinement with said closure wall 64.

A vertical rod 68, suitably and conveniently connected, as at 69, to a midportion of an upper surface of the float 34, extends freely upwardly through and in spaced relation to an upstanding tube 70 having its lower end fixed, as at 71, in the upper wall of the housing 32. The vertical rod 68 and the upstanding tube 70 are disposed substantially centrally of the upstanding vessel 62 in spaced relation to its side wall, and upper portions of said vertical rod are slidably guided in vertically alined bushings 72 and 73 supported by the closure wall 64 and the base 67, respectively.

The water flow control valve 39 is suitably and conveniently supported, as at 74, upon the casting or cylinder head 20, and an actuating lever 75 for the valve stem 48 is rigidly secured, as at 76, to an exterior portion of said valve stem to extend in general direction toward the vertical rod 68. A bifurcated exterior end portion of the actuating lever 75 provides spaced apart arms 77, 77 at opposite sides of said vertical rod 68 and between the spaced apart legs 66, 66, and the vertical rod rigidly supports a cross pin 78 having its opposite end portions freely situated in elongated slots 79, 79 in the spaced apart arms 77, 77 and slidably arranged in vertical slots 80, 80 in said spaced apart legs 66, 66. Roller members on the cross pin 78 and in the elongated slots 79, 79 are indicated 81, 81, roller members on said cross pin and in the vertical slots 80, 80 are designated 82, 82, and retainer pins in the outer ends of the cross pin 78, at the exterior sides of the spaced apart legs 66, 66, are represented 83, 83.

Upon rise of sewage in the float chamber 33, due to back-up of sewage in the sewer, the float 34 is elevated to cause the vertical rod 68 and the cross pin 78 to lift the adjacent end portion of the actuating lever 75 to move the valve member to its position as in Fig. 9, thus to permit flow of water under head pressure from the inlet pipe 52 to the end portion of the tubular member 22 adjacent the casting or cylinder head 20 and flow from the end portion of said tubular member adjacent the casting or cylinder head 21 to the outlet pipe 54. The water entering the casting or cylinder head 20 end of the tubular member 22 under head pressure obviously will cause the piston 30 to be depressed and the gate valve 17 to be moved to closed condition of the sewer drain pipe 15.

Upon fall of sewage in the float chamber 33, when back-up in the sewer is discontinued, the float 34 is lowered by gravity to cause the vertical rod 68 and the cross pin 78 to depress the adjacent end portion of the actuating lever 75 to move the valve member 43 to its position as in Fig. 10, thus to permit flow of water under head pressure from the inlet pipe 52 to the end portion of the tubular member 22 adjacent the casting or cylinder head 21 and flow from the end portion of said tubular member adjacent the casting or cylinder head 20 to the outlet pipe 54.

The water entering the casting or cylinder head 21 end of the tubular member 22 under head pressure obviously will cause the piston 30 to be elevated and the gate valve 17 to be moved to open condition of the sewer drain pipe 15.

The upper portion of the float 34 carries a suitable valve 84 of structure to snugly engage a valve seat 85, provided by the lower end of the upstanding tube 70, when said float is at its highest elevation. The valve 84 and the valve seat 85 evidently cooperate with each other to seal the float chamber 33 against the passage of sewage from said float chamber into said upstanding tube 70 when the float has been elevated to position above which there could be possibility of ingress of sewage to the upstanding tube.

By reason of the fact that the interior surface of the lower wall 35 of the housing 32 slants smoothly downwardly and inwardly from the cylindrical wall of said housing to the opening 37 in its lower wall, the float chamber 33 is self-flushing. Thus, no clogging of said float chamber, which would interfere with the transmission of back-up pressure to the float chamber and also interfere with proper movements of the float, is liable to occur.

The apparatus incorporates a construction and arrangement, including the upstanding vessel 62 and the upstanding tube 70 as parts thereof, providing a liquid seal for and above the float chamber 33, the obvious purpose of the liquid seal being to preclude the passage of odors from the float chamber 33 up through said upstanding tube 70 and into the interior of a house or other structure in which the apparatus may be situated. Of course, odors, if any, can pass freely from the float chamber through the vertical vent pipe 61 to outside atmosphere.

The upper end of the upstanding tube 70 terminates at an intermediate portion of the upstanding vessel 62, adjacent the midheight of said upstanding vessel in the disclosed embodiment of the invention, in considerably spaced relation to the upper wall of the housing 32. A confining member in the upstanding vessel 62 consists of a tubular element 86 open at its lower end and closed at its upper end by a base wall 87 rigidly secured, as at 88, to the vertical rod 68. The tubular element 86 is of greater diameter than the upstanding tube 70 and of smaller diameter than said upstanding vessel 62. The base wall 87 is secured to said vertical rod 68 at a location spaced from the float 34 such that when said float is at its lowermost position, said base wall 87 will be situated in spaced relation to the upper end of the upstanding tube 70 and the lower end of the tubular element 86 will be in spaced relation to the upper wall of the housing 32, about as disclosed in Fig. 2 of the drawings, and when the float is at its uppermost position said lower end of said tubular element yet will be at an elevation below said upper end of said upstanding tube.

The closure wall 64 on the upper end of the upstanding vessel 62 includes an opening having therein a funnel 89, and the outlet pipe 54 includes an outlet end above and in communicating relation to said funnel.

The upstanding vessel 62 and the tubular element 86 are adapted to contain water up to the location of the upper end of said upstanding tube 70 so that odors, in order to escape from the float chamber 33 by way of the upstanding tube, would be required to travel along a tortuous

path first upwardly through said upstanding tube, thence downwardly through water in said tubular element and finally upwardly through water in said upstanding vessel. Stated otherwise, there will be water in the upstanding vessel 62 and the tubular element 86 up to a level in horizontal alinement with the upper end of the upstanding tube 70, and the confining member, constituted as said tubular element and the base wall 87, comprises, together with said upstanding tube and said upstanding vessel, an instrumentality for precluding passage of odors from the float chamber 33.

Although water may be manually poured through the funnel 89 into the upstanding vessel 62 until this contains water up to the desired level, said upstanding vessel conveniently can be supplied with water exhausted from the tubular member 22 by way of the outlet pipe 54. The capacity of said tubular member desirably may be such that water discharged therefrom during a single stroke of the piston 30 will be sufficient to fill the upstanding vessel 62 up to the location of the upper end of the upstanding tube 70. Clearly, water above the location of said upper end of said upstanding tube will flow by gravity through the upstanding tube and the float chamber to the sewer drain pipe 15 when the float 34 is in a depressed position. The capacity of the portion of the upstanding vessel 62 above the upper end of said upstanding tube 70 will be of sufficiently great magnitude to contain water discharged from the tubular member 22 during a stroke of the piston 30 while the float 34 is elevated. Immediately when said float 34 commences to fall, to cause the valve 84 to become removed from the valve seat 85, water contained in said upstanding vessel above the upper end of the upstanding tube 70 will commence to flow by gravity through said upstanding tube and the float chamber 33 to said sewer drain pipe 15. Water exhausted from the tubular member 22 in excess of that utilized in the upstanding vessel 62 for liquid sealing purposes passes harmlessly to the sewer by way of the upstanding tube 70, the float chamber 33 and the sewer drain pipe 15.

The gate valve 17 may be of ordinary or preferred construction. As disclosed, said gate valve includes a pair of oppositely disposed plates adapted to be urged against oppositely disposed circumferential valve seats of the casing 16 when the gate valve is in closed position and to be removed from said circumferential valve seats when said gate valve is in open position.

Attention is called to the fact that all of the working elements of the apparatus are substantially in a single plane which also includes the sewer drain pipe 15 and the gate valve casing 16.

What is claimed is:

1. In an apparatus of the character described, a sewer drain pipe, a valve for controlling said sewer drain pipe, a cylinder, a piston in said cylinder, a member connecting said sewer control valve to said piston, means including water under pressure from a water supply system for actuating said piston in opposite directions to open and close said sewer drain pipe control valve, said water under pressure being adapted to be supplied to said cylinder at either side of said piston, and mechanism for regulating the supply of water to said cylinder, said mechanism comprising an inlet from said water supply system, an outlet for water, separate water connections leading to said cylinder at opposite sides, respectively, of

said piston, a water connection leading from said inlet to each of said mentioned separate water connections, respectively, a rotary valve operable selectively to allow passage of water to each of said last mentioned water connections, a water connection leading from each of said mentioned separate water connections to said outlet, said rotary valve being operable selectively to control passage of water from each of said water connections leading from said mentioned separate water connections to the outlet and in such manner that when the rotary valve is actuated to allow passage of water to the portion of said cylinder at one side of said piston passage of water to the opposite side of said piston will be precluded and so that when there is communication between said inlet and the portion of said cylinder at one side of said piston there is communication between the portion of said cylinder at the opposite side of said piston and said outlet, a stem for said rotary valve, an actuating lever rigid with said stem, and means for swinging said lever in response to rise and fall of liquid level in said sewer drain pipe.

2. The combination as specified in claim 1 wherein said means for swinging said actuating lever includes a float as a part thereof.

3. In an apparatus of the character described, a sewer drain pipe, a housing providing a chamber for sewage to which said sewer drain pipe is open, a member in said chamber adapted to rise and fall with rise and fall of level of sewage in said sewer drain pipe and chamber, means including a vertical rod for guiding said member, and a water seal for an upper portion of said chamber constituted as a vessel upon said housing and adapted to receive water, a vertical tube within said vessel and open to said chamber and a confining member consisting of a base wall secured to said vertical rod and a downwardly extending tubular element rigid with said base wall and open at its lower end disposed within and in spaced relation to said vessel and in spaced, surrounding relation to said vertical tube.

4. In a sewer flooding control apparatus for preventing back-up flooding from a sewer drain pipe, a valve for controlling said sewer drain pipe, means including an actuating lever and water under pressure for actuating said valve, a housing providing a chamber for sewage to which said drain pipe is open, a member in said chamber actuated in response to rise and fall of sewage in said sewer drain pipe for regulating said means, means for guiding said member including a vertical rod to which said actuating lever is operably connected, a water seal for an upper portion of said chamber constituted as a vessel upon said housing adapted to receive water, a vertical tube within said vessel and open to said chamber and a confining member consisting of

a base wall secured to said vertical rod and a downwardly extending tubular element rigid with said base wall and open at its lower end disposed within and in spaced relation to said vessel and in spaced, surrounding relation to said vertical tube, and mechanism for utilizing waste water from said actuating means to the provision of said water seal.

5. In an apparatus of the character described, a sewer drain pipe, a valve for controlling said sewer drain pipe, a cylinder, a piston in said cylinder, a member connecting said sewer control valve to said piston, means including water under pressure from a water supply system for actuating said piston in opposite directions to open and

close said sewer drain pipe control valve, said water under pressure being adapted to be supplied to said cylinder at either side of said piston, and mechanism for regulating the supply of water to said cylinder, said mechanism comprising an inlet from said water supply system, an outlet for water, first and second water connections leading to said cylinder at opposite sides of said piston, a rotary valve operable selectively between a first position allowing passage of water from said inlet to said first water connection and from said second water connection to said outlet and a second position allowing passage of water from said inlet to said second water connection and from said first water connection to said outlet, 15

5

a stem for said rotary valve, an actuating lever rigid with said stem, and means for swinging said lever in response to rise and fall of liquid level in said sewer drain pipe.

EDWARD C. HANSON.
